United States Patent

Des. 234,388
Patented Feb. 25, 1975

234,388

CREDENZA

Ronald R. Hodges, Grandville, and Jack Hockenberry,
Grand Rapids, Mich., assignors to Steelcase Inc.,
Grand Rapids, Mich.

Filed May 22, 1973, Ser. No. 362,857

Term of patent 14 years

Int. Cl. D6—04

U.S. Cl. D6—164

FIG. 1

FIG. 2

FIG. 3

FIG. 6

FIG. 4

FIG. 5

FIG. 7

FIG. 1 is a perspective view of a credenza embodying the design of the invention;

FIG. 2 is a front elevational view of the credenza;

FIG. 3 is an end elevational view of the credenza;

FIG. 4 is a rear elevational view of the credenza;

FIG. 5 is a top plan view of the credenza;

FIG. 6 is a cross-sectional view taken along plane VI—VI of FIG. 2; and

FIG. 7 is a front elevational view of an alternative embodiment credenza embodying the design of the invention.

We claim:

The ornamental design for a credenza, substantially as shown.
